DESIGN FOR A SHOE

Samuel Weinstat, New York, N. Y., assignor to Valley Shoe Corporation, St. Louis, Mo., a corporation of Missouri

Application October 22, 1934, Serial No. 53,721

Term of patent 3½ years

To all whom it may concern:

Be it known that I, Samuel Weinstat, a citizen of the United States, residing at the city of New York, State of New York, have invented a certain new, original, and ornamental Design for a Shoe, of which the following is a specification, reference being made to the accompanying drawing, forming a part thereof, in which Figure 1 is a side elevational view and Figure 2 is a plan view of a shoe embodying my design.

I claim—

The ornamental design for a shoe, substantially as shown.

SAMUEL WEINSTAT.
